R. THORNTON

SECTION BEAM

Filed Jan. 18, 1921

Inventor:
Ray Thornton
By Geo. N. Woodward,
atty.

UNITED STATES PATENT OFFICE.

RAY THORNTON, OF NEW BEDFORD, MASSACHUSETTS.

SECTION BEAM.

Application filed January 18, 1921. Serial No. 438,112.

To all whom it may concern:

Be it known that I, RAY THORNTON, a citizen of the United States, and a resident of New Bedford, in the county of Bristol and State of Massachusetts, have invented a new and useful Improvement in Section Beams, of which the following is a specification.

My invention relates to section-beams, and more particularly to section-beams of the type shown in my prior Letters Patent No. 1,239,744 dated September 11, 1917, and No. 1,297,751 dated March 18, 1919.

A section-beam is a large bobbin designed to hold about four hundred pounds of warp or filling yarn for shipment, and is provided with a fixed longitudinal shaft arranged to be mounted for rotation when the yarn is unwound for transfer to a loom-beam or when the section-beam itself is used as a loom-beam.

Heretofore section-beam shafts were permanently secured thereto and shipped therewith, and experience has shown that the projecting ends of the shaft become bent or otherwise deformed in transit. This results in an uneven rotation of the section-beam when the yarn is being unwound therefrom for transfer to the loom-beam and in an irregular winding of the yarn on the latter, and when a section-beam is used as a loom-beam as is sometimes done especially in weaving fabrics for automobile tires, the uneven movement of the beam, known as "jumping ahead", causes bad spots in the cloth.

The object of my invention is to provide a section-beam having a shaft which can readily be removed therefrom before shipment and which, being retained in the weaving mill, is not subjected to distortion of its shape by the rough usage which a shaft permanently affixed to the section-beam of the prior art always receives in transit.

By means of my invention not only are the foregoing difficulties overcome, but also a further advantage is obtained in that the section-beam can be loaded vertically on the trucks and freight cars thus economizing space and eliminating the necessity for the padding that must be placed around the full beams when they are loaded horizontally.

With the foregoing object in view my in-

vention comprises a section-beam preferably having cross-banded wooden heads such as described in my prior patents provided with a removable shaft and means, such as rods extending through the barrel, independent of the shaft for clamping the heads to the barrel. A convenient means for removably securing the shaft to the barrel and at the same time centering the same consists in a metallic pipe arranged axially of the barrel on which are mounted the usual disks which support the barrel slats, and bushings having threaded engagement with the shaft near the ends thereof and arranged to accurately fit into the ends of said pipe.

My invention will be described by reference to the drawings which accompany and form a part of this specification, and which illustrate one form of shaftless section-beam that has given good results in practice.

In the drawings—

Figure 1 is a longitudinal section of a section-beam embodying my invention;

Fig. 2 is an end view;

Fig. 3 is a transverse section taken on the line 3—3 of Fig. 1; and

Fig. 4 is a plan view of the removable shaft and the bushings threaded thereto near the ends thereof.

In the particular drawings selected for more fully disclosing my invention, 10 represents the barrel made up as usual of a number of slats or staves 11 nailed or otherwise attached to the disks 12 which are mounted on the axially disposed metallic pipe 13, the ends of which are shown as 14 flush with the outer faces of the heads 14.

As illustrated the heads 14 are each formed of 3 layers of wood 15, 16 and 17 and each layer is made up of 3 bands as indicated in Fig. 2, the meeting edges of 18 said bands being dove-tailed or otherwise suitably united as indicated at 16.

While I am aware that various means independent of the shaft may be employed for clamping the heads to the barrel as distinguished from section-beams of the prior art in which this function is performed by nuts threaded to the shaft and co-operating with the outer faces of the heads, I prefer to employ rods 17 herein shown as four in number which pass through the barrel and heads, and to the end of which nuts 18 are threaded, the outer faces of the heads be-

ing countersunk to receive said nuts so that the latter will be flush with said outer faces.

Inasmuch as the ends of the pipe 13 and the nuts 18 are flush with the outer faces of the heads, and the latter, as shown, have plane surfaces, the section beam may be placed in upright position so that, as above stated, the beams may be loaded vertically on trucks and freight cars with the advantages above pointed out.

A convenient means for securing the disks 12 to the pipe 13 consists as shown of the flanges 19 secured to said disks by the screws 20 or in any other suitable manner and attached to said pipe by the set-screws 21.

Inasmuch as the usual metallic pipes of commerce are not of absolutely internal diameter, I prefer to employ a shaft 22 of smaller diameter than the bore of the pipe 13 and to provide means for performing the double function of accurately centering said shaft with respect to the section-beam and of detachably securing the same to the structure.

In the particular instance illustrated in the drawings, I show bushings 23, 23 threaded to the shaft near the ends thereof and accurately fitted into the ends of the pipe, for which purpose the bore of the pipe will be accurately machined a short distance from the ends thereof. The bushings 23, 23 are each provided with a polyangular flange 24 the inner face of which rests against the outer face of one of the heads, and which are arranged for receiving a wrench, so that when the bushings are forced along the screw-threaded portions of the shaft toward each other, the said flanges will take against the heads and thereby hold the shaft firmly in position.

Preferably the heads are provided with the metallic rims 25 which are grooved to receive the restraining cord employed when the thread is unwound.

Having thus described an illustrative improvement of my invention without however

limiting the same thereto, what I claim and desire to secure by Letters Patent is,—

1. A section-beam comprising a barrel, heads for the same, the outer surfaces of said heads being plane, a removable shaft for said barrel, the ends of said shaft extending beyond said heads, and means independent of said shaft for clamping said heads to said barrel, the said means not extending beyond the plane of the outer face of said heads and the said section-beam when assembled with the shaft removed having smooth outer ends.

2. A section-beam comprising a barrel, heads for the same, a pipe running through said barrel, the ends of said pipe being flush with the outer faces of said heads, a removable shaft in said pipe, the ends of said shaft extending beyond the ends of said pipe, means threaded to said shaft for centering said shaft with respect to said pipe, and means independent of said shaft for clamping said heads to said barrel.

3. A section-beam comprising a barrel, heads for the same, a pipe running through said barrel, the ends of said pipe being flush with the outer faces of said heads, a removable shaft in said pipe, the ends of said shaft extending beyond the ends of said pipe, bushings threaded to said shaft near the ends thereof and fitting into the ends of said pipe, and means independent of said shaft for clamping said heads to said barrel.

4. A section-beam comprising a barrel, heads for the same, a pipe running through said barrel, a removable shaft in said pipe, the ends of said shaft extending beyond the ends of said pipe, bushings threaded to said shaft near the ends thereof and fitting into the ends of said pipe, and rods passing through said barrel and clamping said heads against the ends of the same.

In testimony whereof, I have hereunto subscribed my name this 14th day of Jan. 1921.

RAY THORNTON.
